Fig 3

To all whom it may concern:

Be it known that I, Alexander Rauchman, a citizen of the United States, residing in the county of New York and the State of New York, have invented a new, original, and ornamental Design for a Combined Speaker Enclosure, Television, Radio, and Record Player Cabinet, of which the following is a specification, reference being had to the accompanying drawings, forming part thereof.

Fig. 1 is a front elevational view of a combined speaker enclosure, television, radio, and record player cabinet showing my new design;

Fig. 2 is a top plan thereof;

Fig. 3 is a side elevational view thereof; and

Fig. 4 is a front elevational view thereof with the doors in open position.

I claim:

The ornamental design for a combined speaker enclosure, television, radio, and record player cabinet, as shown.
